UNITED STATES PATENT OFFICE.

GEORGES LOUIS WILLAIME, OF PARIS, FRANCE.

AUTOMATIC LIQUID-WEIGHING MACHINE.

Application filed April 4, 1925, Serial No. 20,633, and in France April 22, 1924.

The object of my invention is to provide an automatic liquid-weighing machine.

In order to make my said invention more clearly understood, I have illustrated, as an example, an embodiment thereof in and by a drawing appended hereto and wherein:

Figure 1 is a vertical section of my machine on line 1—1, Fig. 3;

Figure 2 is a part-sectional side view 10 thereof.

Figures 3 and 4 are sections along lines 3—3 and 4—4, respectively, of Fig. 1.

Figures 5 and 6 are, respectively, a part-sectional side view of a modification and a 15 section along line 6—6 thereof.

In all the figures the same reference letters denote the same parts.

My weighing-machine is composed essentially of a reservoir R into which is fed the liquid to be weighed; a second reservoir F forming a float inside the first one; and a weight M movable within reservoir F and corresponding to the quantity of liquid discharged at each weighing. Said weight M 20 will be operated, that is to say alternately lifted and lowered, by a hydraulic device, the piston P of which is adapted to alternately release and engage weight M by means of hooks K.

Reservoir R is provided with an inlet valve S for the liquid having a counterpoise c', and is additionally provided with a sloping bottomed circular gutter designed to collect liquid overflowing from reservoir R; 25 said gutter has at its lowest part a double valve j—j' fitted with a counterpoise c and permitting the liquid to be discharged either for shipment or into a tilting vessel V, according as the counterpoise c is thrown to the right or to the left. (Figure 2). The hydraulic device, which is a single action one, comprises a distributor d of any type (piston, slide-valve or even a two-way cock) which sometimes permits water from the 30 charging trough to be led to the cylinder of the device, and sometimes permits this cylinder, which then constitutes a hydraulic brake, to be put into communication with the outlet.

From the foregoing explanation it becomes obvious that in order to effect a weighing, the following operations will have to be accomplished successively, to wit:

1. Bring up weight M, thus releasing the float F, allow the liquid to come in; open

valve j' and wait until the liquid overflows the inner edges of reservoir R.

2. At this moment close inlet valve S.

3. Float F having become balanced as the excess of liquid which has overflowed is 60 evacuated through valve j'; reverse the double valve and open valve j.

4. Operate the distributor d to let down piston P which is at the time at the top of its travel. Due to this motion weight M will 65 descend and rest on the bottom of float F which it will then tend to bring down until a quantity of liquid equal to weight M has been evacuated by overflowing into the gutter and then discharged through valve j. 70 This will happen when, the piston having gone down low enough, hooks K have been released from contact with suspension ears K' and the F and M set has become a free-float.

These four operations, which constitute the complete cycle, will then begin again and continue being repeated in an automatic manner.

In fact, the piston being at bottom of its 80 travel, as above explained and as shown by the drawing, tappet T will act on the distributor, thus opening the cylinder to water admission.

The piston will then go up, hook up weight M and the finger t carried by float-reservoir F will act on the counterweighted lever of the inlet valve S to open that valve.

Continuing upwards float F will, by means of a second finger t', reverse the double valve 90 j—j', opening valve j'.

A moment afterwards, the piston having reached the top of its travel, the float gets near it too, the level of the liquid tending to become flush with the overfall constituted 95 by the edge of reservoir R.

After flush level is reached, overflow takes place and this overflow is utilized to start the above-indicated operations 2, 3 and 4.

The part that, utilizing the overflow, is 100 employed to actuate the necessary operating motions is the container or vessel V, supported by a forked lever the other end of which carries a balancing counterweight D. Said container has, at its lower part, an outlet the aperture of which can be varied according to the position of a thrust valve B, which valve is never quite shut.

Container V having received a sufficient 110 quantity of overflowed liquid will sink down

and shut valve S, the counterpoise of said container acting on the counterweight c' of said valve (movement 2).

Container V being lowered, its contents will run out through the outlet of the container into a discharge trough N, and as soon as it has emptied it will be raised by the action of its counterweighted lever, the terminal D² of which will engage a hinged 10 tappet r carried by a vertical control rod U and likewise move said rod upward. A finger t'' fixed to the control rod will engage and operate the double valve j, j', during this movement, as indicated in step 3; the upper end of the rod being attached to a cross-head d² to which the stem of the piston valve d³ of the distributor is also attached.

Due to the upward movement of vessel 20 V and through the same control rod U operation 4 of the distributor will be effected.

As will be apparent the working of the device is automatic and dependent only on admission of the liquid to be weighed.

25 If, in fact, such admission should cease on account of the working being stopped through any cause, piston P having gone up to the top of its travel would remain there, kept by the water pressure, while float F 30 would be immobilized at any point of its upward travel until a new admission of liquid sends it up again.

Accuracy of weighing will be the greater the less the speed with which float F arrives 35 at its lowest position and the smaller therefore the alternate oscillation imparted to the float before it becomes finally balanced.

In order to decrease the ultimate downward speed of float F as well as the amplitude of oscillation three devices may, for instance, be used:

40 1. As diagrammatically illustrated on the drawing, piston P may be arranged so as to mask, at the bottom of its travel, the water outlet. Outflow being rendered more difficult the down-motion speed of float F will be decreased. Indeed, consideration of the law governing the downward motion of said 45 float will show that the reaction push of the liquid increasing according to sinking, the speed will already tend to go on decreasing.

50 2. Float F's immersed cylindrical part may be fitted with one or a plurality of fins which will increase friction and damp oscillations. The drawing shows a fin or paddle X made up of two angle-pieces.

55 3. The edge or rim constituting an overfall sill for reservoir R may not be horizontal and continuous but have a notch such as W (or a series of indented notches) which will render more accurate the final balancing of the float at a precise level, such level being determined by the lower secondary 60 sill.

The above described device, is, of course, to be combined with a suitable counter or meter registering the number of oscillations. Of course, also the special arrangement of counterpoises, rods, and tappets shown by 70 the drawing is merely indicative and not limitative, it being permissible to effect the connections required for operating the various valves or distributors in different ways which in no manner affect the essential features of the machine.

In the modified arrangement represented in Figures 5 and 6, the hydraulic device is located at one side of reservoir R and parallel with the axis thereof, the weight being 80 lifted by a cable and pulley connection. The parts common to this construction and the one first described are indicated by the same reference letters as in the first construction but with the addition of the prime mark. 85 The parts designated L in Figures 5 and 6 are three vertical columns which jointly support at their tops a frame L' carrying a pair of guide pulleys L² over which passes a cable L³ connected at opposite ends with 90 the weight M' and the piston P'. The distributor d' is here shown as of the plug valve type instead of the piston valve type. The figures indicated represent the apparatus in the piston-ascent stage, the distributor valve having been opened by means of a lever m connected to the control rod U', which latter has itself been actuated by the ascent of vessel V' after its emptying, exactly as in the first form. The piston P' 95 descends under the influence of the pressure of the water admitted through the distributor d', raises weight M' and thus enables float F' to rise by flotation on the liquid to be weighed which enters through the then 100 open valve S.

Having now particularly ascertained and described the nature of my said invention as well as the manner in which the same is to be performed, I declare that what I claim is:

110 1. Liquid weighing apparatus, comprising a reservoir to receive liquid to be weighed; an overflow gutter on the reservoir having a discharge outlet; an inlet valve to control the supply of liquid to the reservoir; a rising-and-falling float tank in said reservoir; a weight movable within and relatively to the tank to cause the same to displace into the overflow gutter a predetermined quantity of liquid; a device for raising and lowering the weight; and a train of 115 connections between said device and said valve for automatically controlling the movements of the float tank and weight.

120 125 2. Liquid weighing apparatus, comprising a reservoir to receive liquid to be weighed; an overflow gutter on the reservoir having a discharge outlet; an inlet valve to control the supply of liquid to the reservoir; a rising-and-falling float tank in said reservoir; a 130

weight movable within and relatively to the tank to cause the same to displace into the overflow gutter a predetermined quantity of liquid; a hydraulic device for raising and lowering the weight; a distributor for regulating the supply of motive fluid to said device; and a train of connections between said distributor and valve for automatically controlling the movements of the float tank and 10 weight.

3. Liquid weighing apparatus, according to claim 2, in which the hydraulic weight-operating device embodies a cylinder and piston, the latter having connections with 15 the weight; and in which the connecting train between the distributor and the inlet valve embodies a control rod connected with a piston valve comprised in said distributor, so that said piston valve is shifted in accordance with the movements of said rod.

4. Liquid weighing apparatus, comprising a reservoir to receive liquid to be weighed; an overflow gutter on the reservoir having a discharge outlet; an inlet valve to control 25 the supply of liquid to the reservoir; a rising-and-falling float tank in said reservoir; a weight movable within and relatively to the tank to cause the same to displace into the overflow gutter a predetermined quantity 30 of liquid; a device for raising and lowering the weight; and a train of connections between said device and said valve for automatically controlling the movements of the float tank and weight, said train including 35 a movable vessel disposed exterior to the reservoir and adapted to receive the liquid discharged from the overflow gutter.

5. Liquid weighing apparatus, according to claim 4, in which the movable vessel is 40 supported by a counterweighted lever which normally holds it in raised position, but which is rocked and thereby caused to close the inlet valve when said vessel sinks under the weight of the liquid discharged into it 45 from the gutter.

6. Liquid weighing apparatus, comprising a reservoir to receive liquid to be weighed; an inlet valve to control the supply of liquid thereto; a rising-and-falling float tank in 50 the reservoir; a weight movable within and relatively to said tank to cause the same to displace a predetermined quantity of liquid from the reservoir by overflow; a device for operating said weight; a controller for said 55 device; and a device to receive the overflow

from said reservoir having separate means associated with it for operating said controller and said inlet valve.

7. Weighing apparatus, according to claim 6, in which the receiving device comprises a vertically-movable vessel disposed exterior to the reservoir; and in which the controller-operating means and the valve-operating means are respectively actuated on the upward and downward movements of said vessel.

8. Liquid weighing apparatus, comprising a reservoir to receive liquid to be weighed; an inlet valve to control the supply of liquid thereto; a rising-and-falling float tank in the reservoir; a weight movable within and relatively to said tank to cause the same to displace a predetermined quantity of liquid from the reservoir by overflow; a device for operating said weight; a controller for said device; a rising-and-falling vessel disposed exterior to the reservoir in position to receive the overflow therefrom; a weighted lever whereon said vessel is mounted and tending to raise the same, but yielding when the vessel is filled to permit its descent, said lever adapted to operate the inlet valve during such yielding movement; and means actuated by the upward movement of said vessel when emptied for operating the controller.

9. Liquid weighing apparatus, comprising a reservoir to receive liquid to be weighed; an inlet valve to control the supply of liquid thereto; a rising-and-falling float tank in the reservoir; a weight movable within and relatively to said tank to cause the same to displace a predetermined quantity of liquid from the reservoir by overflow; a device for operating said weight; a controller for said device; a rising-and-falling vessel disposed exterior to the reservoir in position to receive the overflow therefrom; a vertically-movable rod for operating said controller; means tending to move said vessel upward but yielding when the latter fills to permit its descent, said means adapted to operate the inlet valve during such yielding movement; and means for actuating said rod during and consequent upon the upward movement of the vessel.

In testimony whereof I affix my signature.

GEORGES LOUIS WILLAIME.
